2,410,822

HIGH FREQUENCY ELECTRON DISCHARGE APPARATUS

David E. Kenyon, Smithtown, N. Y., assignor to
Sperry Gyroscope Company, Inc., a corporation
of New York

Application January 3, 1942, Serial No. 425,491

13 Claims. (Cl. 250—27.5)

1

This invention relates, generally, to vacuum tube structures and the invention has reference, more particularly, to a cathode structure designed for the production of high current density electron beams. In prior art cathodes for such purposes, great difficulty has been experienced in producing heater coils having very low magnetic fields, said magnetic fields having an undesirable tendency to modulate the electron beam unless special shielding precautions are resorted to. It has also generally been necessary to use oxide-coated emitting surfaces in order to produce usable emission currents, the temperature of the emitting surface being usually limited by the maximum temperature at which the cathode heater element can be operated and still give the device a reasonable life of operation. The present invention discloses a cathode structure relatively free of magnetic fields and whose emitting surface may be operated at elevated temperatures.

The principal object of the present invention is to provide a cathode having an emitting surface portion that is heated by electron bombardment, the electrons for effecting such bombardment being supplied from a second surface.

Another object is to provide means for heating said second surface to a predetermined initial temperature, and switching mechanism for then stopping said heater means and causing the first and second emitter surfaces to heat each other by means of a high voltage alternating current acting from electrons emitted on the adjacent surfaces of the two emitters.

An object is to provide a cathode emission surface relatively free of warping due to thermal effects.

Yet another object is to provide such a cathode structure for the production of cylindrical electron beams.

Still another object is the provision of such a cathode structure for the production of radially projected electron beams.

Yet another object is to provide such a cathode in which all elements in use in other than starting operations are heated by means of high voltage, low current electron beams, thus minimizing undesirable effects due to magnetic fields.

An object is to provide a cathode structure in which heating filaments are operated only in starting emission, thus allowing said emitting surfaces to be operated at very elevated temperatures.

A further object of the invention is the provision of a cylindrical, radial or other beam producing cathode in which the heating filament

2

used in starting emission does so in only a limited area of the emitter surface, the emission being spread from the original hot spot after the current through said heater element is turned off.

5 Other objects and advantages will become apparent from the specification, taken in connection with the accompanying drawings wherein the invention is embodied in concrete form.

10 In the drawings:

Fig. 1 is a fragmentary perspective longitudinal cross-sectional view and wiring diagram of a form of the invention.

15 Fig. 2 is a longitudinal cross-sectional view, partly in elevation, showing an application of the cathode disclosed in Fig. 1.

Fig. 3 is a cross-sectional view of a modified form of a portion of Fig. 1.

20 Fig. 4 is a fragmentary longitudinal cross-sectional view of another modified form of the present invention.

Fig. 5 is a plan view on a reduced scale of the structure shown in Fig. 4, taken along the line 5—5 of Fig. 4.

25 Fig. 6 is a fragmentary longitudinal cross-sectional view of a further modification of the present invention.

Similar characters of reference are used in all 30 of the above figures to indicate corresponding parts.

Referring now to Fig. 1, there is shown a preferred form of the present invention. Spiral heater element 1, supported by leads 2 and 3 which may pass through the conventional type 35 glass press (not shown) usually used in vacuum tube structures to provide current lead and support means, is positioned preferably centrally within a heat shield inner wall 4, leads 2 and 3 passing through holes 5 and 6 in end wall 7 of the heat shield. This heat shield has a folded back portion in the form of a cylindrical wall 8 spaced outwardly from and concentric to wall 4, to provide more effective heat shielding by the well known double-wall effect. Wall 8 extends 40 below end wall 7 of said heat shield, and pressed into the inner diameter of wall 8 is a second end wall 9 for the heat shield, leads 2 and 3 passing through holes 10 and 11 in wall 9.

50 Positioned centrally above spiral heater element 1 is disk 12 which may be somewhat dished, in which case the convex side of disk 12 faces heater 1. Somewhat spaced from disk 12 on the side thereof away from heater 1 is a second disk 13 which may also be dished similarly to disk 12. Heater 1 may be of tungsten and disks 12 and 13

of tantalum, columbium, nickel, or other metal of low electron work function; or heater 1 and disks 12 and 13 may be oxide-coated with any of the well known barium, strontium, etc., emission materials. On the side of disk 13 away from disk 12 is a focussing element with a central aperture nearly as large in diameter as the diameter of disk 13 and consisting of an inclined annular portion 14, a flat annular surface 15 substantially perpendicular to the axis of symmetry of the structure, and a cylindrical wall surface 16 extending from surface 15 concentric to heat shield wall 8 and of somewhat greater diameter. Focussing shield 14, 15, 16 may be supported by three leads 17, 18, 19 spaced 120° apart and extending into the glass press of the vacuum envelope surrounding the cathode. Focussing shield 14, 15, 16, supports, in turn, disk 13 by means of angularly spaced wires 20, preferably symmetrically disposed about the axis of the disk, e. g., at 120° intervals in the manner shown in Fig. 3 spot welded to the inner surfaces of shield portion 14 and disk 13. Heat shield 4, 8 may be supported by three angularly spaced leads 21, also extending into the aforementioned glass press.

Disk 12 may be supported by three angularly spaced leads 24 projecting radially through holes 29 and 30 in walls 4 and 8 of the heat shield. Leads 24 are supported by and are equally spaced about a current distributor such as a ring 25 concentric to wall 16, which ring in turn is supported from the glass press by three leads 26, 27, 28, which may be mutually spaced at 120°. The cathode structure may be positioned at a proper distance from an accelerating electrode 31, which may contain a central aperture 33 concentric to the axis of symmetry of the cathode, containing therein grid bars 32, whose function is to further improve the shape of the electron beam to be projected through aperture 33.

In use, there is preferably applied to spiral heater 1 a relatively low alternating voltage by means of leads 2, 3 from the connected secondary 34 of transformer 35. A moderate alternating voltage is also applied between lead 2 and disk 12 from the secondary 36 of transformer 35 via lead 26, ring 25 and lead 24. Preferably a relatively high alternating voltage is applied between disks 12 and 13 from a transformer 37 by way of lead 17, focussing shield 16, 15, 14, and wires 20 on the one side and lead 26, ring 25 and lead 24 on the other. A moderately high direct current voltage is applied between emitter 13 and electrode 31 from power supply 39 via lead 17, focussing shield 16, 15, 14, and wires 20 on the one side and wire 38 on the other. Transformer 35 is shown supplied through a time actuated relay 43, transformer 37 through a time delay relay 41, and power supply 39 through a time delay relay 42, all from any suitable alternating current supply to which connection is made by leads 40, 40'.

When it is desired to put the cathode into operation, the following procedure is used. Switch 44 is closed, time delay relays 41 and 42 being open so that no current flows to transformer 37 or power supply 39. Time actuated relay 43 is of the well known commercial type which closes its circuit immediately when switch 44 is closed, being set to open such circuit after any desired predetermined time interval. With switch 44 closed, current from transformer secondary 34 heats filament 1, and the alternating current voltage appearing between heater 1 and disk 12

causes electrons emitted from heater 1 to strike disk 12 with high velocity, thus heating disk 12 to a temperature such that its upper side also begins to emit electrons. At this time, time actuated relay 43 has been set to open its associated circuits, and time delay relay 41 closes, thus placing a moderately high alternating current voltage between disks 12 and 13. By energizing the disks 12 and 13 through symmetrically disposed leads 20 and 24 respectively, the magnetic fields produced by the flow of alternating current into the disks neutralize one another and inhibit alternating current modulation of the electron stream. Electrons being emitted from disk 12 are accelerated toward disk 13 during alternate half cycles and impinge upon said disk 13 with high velocity, thus heating it to incandescence. At the time disk 13 is raised to a sufficient temperature, it begins to emit electrons from both surfaces. Those emitted from its under surface are accelerated toward disk 12 striking the latter. The alternating current voltage between disks 12 and 13 thus maintains both at a proper temperature.

Time delay relay 42 is set to close its associated circuit at the time when the upper surface of disk 13 has reached a sufficient temperature to emit electrons. Relay 42 then applies a high direct accelerating voltage between emission surface 13 and electrode 31.

Electrode 31 and its contained aperture 33 and grids 32, and focussing shield 14, 15, 16 are so designed that there is projected an electron beam of uniform round cross-section into the space on the side of electrode 31 away from emitter 13. Thus, it is seen that when the cathode is in its final state of operation the heating and accelerating currents involved are high voltage, low current ones, and that the only alternating heating voltage involved is well shielded inside of members 4, 8, 12, 13, 14, 15, 16. Further, the final temperatures of emission sources 12 and 13 are not determined by a resistance heater unit such as the spiral heater 1, and since this spiral heater 1 is in use only in starting the cathode, its life time is greatly increased. In fact, disks 12 and 13 may even be operated at temperatures much higher than those at which oxide-coated emitters are usable, so that pure metal emitters of tantalum, columbium and similar metals may be used. It is evident to one skilled in the art that a variety of starting devices are usable to give the desired starting cycle, so that the system of relays shown is intended to be purely illustrative.

A cathode producing such an electron beam has many uses, such as in beam power tubes, cathode ray tubes, in electron beam velocity modulating tubes such as those disclosed in patents, No. 2,242,275 entitled "Electrical translating system and method," issued May 20, 1941, to Russell H. Varian and No. 2,259,690 entitled "High frequency radio apparatus," issued October 21, 1941, to John R. Woodyard, William W. Hansen, and Russell H. Varian and in other types of electron tubes.

In Fig. 2, a cathode of the type described in Fig. 1 is shown mounted in a reflex-type electron beam velocity modulating device of the type disclosed in Patent No. 2,250,511 of Russell H. Varian and William W. Hansen. As therein described, an electron beam is projected through aperture 33 of the accelerating grid electrode 31, passes on through field-free-space tube 45, and is velocity modulated by an ultra high frequency alternating electric field appearing between grids 46 and 47.

said alternating field being generated by a high frequency electromagnetic field of natural frequency characteristic of resonator 48. The velocity modulated electron beam passes on through grid 47 and is reflected in the region near reflector plate 49, said plate 49 being at or near the potential of emitter surface 13. During the time required for the electrons to first pass through grid 46, become reflected by plate 49, and return through grid 46, the velocity modulation has resulted in density modulation, the electron groups thus produced returning energy to the electric field between grids 46 and 47, thus maintaining the electromagnetic field in resonator 48. Ultra high frequency energy may then be removed from resonator 48 by means of well known types of coupling devices (not shown). It is evident to one skilled in the art that beams of various degrees of convergence or divergence may be obtained from such a cathode structure, depending chiefly upon the design of the focussing element 14, 15, 16, or upon the use of cooperating magnetic focussing means.

As shown in Fig. 1, emitter elements 12 and 13 are slightly concave. The degree of concavity is such that the percentage distortion of the disk is very much less for a given temperature change than that obtaining in the case of a flat emitter surface. The structure shown in Fig. 3 may be used in place of the disks 12 and 13 in Fig. 1. In Fig. 3, the convex disks 50, 53 have cylindrical walls or skirts 51, 52 of equal diameter attached to their respective peripheries, extending inwardly so that said walls are separated by a small gap. Such a construction improves freedom from warping due to temperature changes, and forms a more completely closed chamber so that electrons accelerated back and forth between disks 50 and 53 have less chance to migrate out of the space defined between said disks.

Electron beams of annular, radial or other character may be produced by the rotation of the cross-section surface of the device shown in Fig. 1 about an axis external thereto, in any desired manner. Two of the possible resultant configurations are disclosed in Figs. 4, 5 and 6.

Referring to Figs. 4 and 5, there is shown a cathode for the production of an annular beam, of a type which may be used in an electron velocity modulating device such as the high power oscillator shown in Fig. 7 of the aforementioned Patent No. 2,259,690. Enclosed in an annular heat shield composed of annular walls 4', 7', 8' and 9' are two cooperating annular emitters 12', 13'. The electron beam from emitter 13' is improved in form by annular focussing member 14', 15', 16'' and projected toward electrode 31', which may contain annular grid structure 32' in aperture 33', if desired. Focussing ring 14', 15', 16' and emitter 13' are supported by leads 17', 18', 19', heat shield 4', 8', 7', 9', by leads 21', and emitter 12' by ring 25' and leads 26', 27', 28' all of said leads being supported in turn from the glass press of the vacuum tube envelope or by other suitable well known methods.

Starting filament 1 and cooperating leads 2 and 3 may be exactly similar to the starting filament shown in Fig. 1, as is seen in Figs. 4 and 5, or may actually be a figure of revolution as a ribbon, a wire, or any other suitable form. In operation, the simple spiral cathode 1 of Fig. 4 is similar to that of Fig. 1. A proper current is allowed to flow through lead 2, spiral 1, and out lead 3, heating the filament, and a proper alternating voltage is imposed between filament 1 and

emitter 12'. The bombarding action of the electrons from spiral 1 is to heat an approximately circular area of emitter 12' just below and concentric to spiral 1. Emission from a corresponding circular area on the lower surface of emitter 12' then starts, and if a moderately high alternating current voltage is imposed between annular emitters 12' and 13', a corresponding circular area on emitter 13' becomes heated. As time passes, the two heated areas on 12' and 13' spread around these annular members, and the entire surfaces of emitters 12' and 13' become hot enough to emit, the voltages between leads 2 and 3 and between leads 3 and 28' having been removed at the proper time as in the above previously described sequence of events. At approximately the time when the entire lower surface of cathode emitter 13' has become hot enough to emit electrons, a high direct voltage is placed between cathode 13' and electrode 31', thus projecting a cylindrical electron beam through annular aperture 33' and into the space below accelerating electrode 31'.

Fig. 6 illustrates a cathode producing an outwardly radially projected electron beam. Emitter 12'', concentric to spiral filament 54, is illustrated as the figure of revolution of an arc of a circle about the axis of the heater 54. Emitter 13'', is also similar in shape and concentric to emitter 12''. Above and below emitters 12'', 13'' are positioned two short cylindrical boxes 57 and 58, whose walls 4'' and 8'' act as heat shields. Concentric to and attached to emitter 13'' is a focussing element consisting of annular inclined portions 14'', cylindrical wall 15'', and apertured wall 16''. Heater 54 is positioned and has its power supplied by leads 55 and 56, lead 56 may also support heat shield 58. Heat shield 57 may be supported by lead 21''. Emitter 13'' and focussing shield 14'', 15'', 16'' may be supported from leads 17'', 18'', in the conventional manner.

The method of operation of the cathode of Fig. 6 is exactly similar to that of Fig. 1, a radially projected electron beam resulting. It is obvious to one skilled in the art that beams of ring-shaped cross-section, diverging or converging, can be made by placing the axis about which the cross-section of Fig. 1 is rotated at various angles between the two used to produce the structures of Figs. 4 and 6, such cathodes being useful in producing beams of the type shown in Figs. 13 and 15 of the aforementioned prior Patent No. 2,259,690.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. Electron discharge apparatus comprising a substantially planar filamentary element adapted to serve as a source of electrons when heated, a first emitter presenting a relatively large surface area to said element, means connected to said element and said emitter for providing a difference of potential between said element and said emitter whereby electrons leaving said element are caused to bombard said emitter with high velocity, a second emitter adjacently spaced from said first emitter, and means connected to said emitters for providing an alternating voltage be-

tween said emitters whereby said emitters heat each other by mutual electron bombardment.

2. The apparatus defined in claim 1, including time actuated relay means connected to said element for automatically rendering said element inoperable to bombard said first emitter after a predetermined initial heating period.

3. Electron discharge apparatus comprising two substantially parallel electron emitter elements, means in said apparatus supporting said elements in adjacent relation, said supporting means including leads symmetrically disposed with respect to and extending from said elements, means connected to said leads for applying an alternating voltage between said emitter elements so that they heat each other by mutual electron bombardment, said symmetrical disposition of leads tending to neutralize the magnetic effects produced by the flow of current through said leads to said elements, an electron permeable conductive member mounted in alignment with said elements and adjacent the non-bombarded surface of one of said emitter elements, means connected to said one emitter element and said member for applying a substantially unidirectional voltage between said one emitter element and said member for accelerating electrons emitted by said non-bombarded surface, and an electron beam focusing means mounted intermediate said one emitter element and said member.

4. The apparatus defined in claim 3, including a filamentary heater member adjacent the other of said emitter elements for initially heating said other emitter element, and time controlled means connected to said heater rendering said heater inoperable when the non-bombarded surface of said one emitter element becomes electron emissive.

5. Electron discharge apparatus comprising two spaced electron emitter elements, electrical means connected to said elements in a predetermined symmetrical arrangement for applying a relatively high alternating voltage between said elements so that they heat each other by mutual electron bombardment of adjacent surfaces, and beam forming electrode means mounted in alignment with said elements for forming the electrons leaving the non-bombarded surface of one of said emitter elements into an electron beam of substantially uniform cross-section, said emitter element electrical arrangement shielding said beam against undesired magnetic disturbances from heating currents in said emitter elements.

6. Electron discharge apparatus comprising two spaced electron emitters, means in said apparatus adjacent one of said emitters for heating said one of said emitters by electron bombardment, electrical means connected to said emitters for providing an alternating voltage between said emitters such that they heat each other by mutual electron bombardment, time controlled means connected to said heating means and said

emitters for rendering said heating means inoperable after a predetermined period of operation and for applying said alternating voltage between said emitters, an electron beam-control electrode mounted in spaced alignment with the non-bombarded electron emission surface of the other of said emitters, and time controlled means for applying a substantially unidirectional electron accelerating voltage between said other emitter and said electrode.

7. Electron discharge apparatus comprising a heater element, a substantially cup-shaped heat shield partially enclosing said heater element, and substantially parallel spaced emitter elements supported substantially across the open end of said shield, said emitter elements being non-conductively connected with said shield.

8. The apparatus defined in claim 7, including means conductively interconnecting said heater element and said shield.

9. The apparatus defined in claim 7, comprising fixed support means electrically separated from said shield, and means on said support means mounting said emitter elements in said spaced relation.

10. Electron discharge apparatus comprising two spaced electron emitter elements, means connecting said elements for producing an oscillating potential between said elements such that they heat each other by mutual electron bombardment, an electron focusing electrode disposed adjacent a non-bombarded surface of one of said emitter elements, and means supporting said one emitter element from said focusing electrode.

11. Electron discharge apparatus comprising a pair of electron emitter members adapted to be energized by a stream of electrons and mounted in closely spaced adjacent relation to be capable of mutual electron bombardment of adjacent surfaces, and skirt-like peripheral walls on each of said members extending toward each other providing a shield about the electron discharge between said surfaces.

12. Electron discharge apparatus comprising a cathode assembly comprising spaced emitters adapted to heat each other by mutual electron bombardment, means connected to said emitters for energizing said emitters, and means aligned with said assembly and operable only after said energization has proceeded to a predetermined condition for accelerating electrons from a non-bombarded surface of one of said emitters.

13. Electron discharge apparatus comprising a heater element, a substantially cup-shaped heat shield partially enclosing said heater element, an emitter element supported substantially across the open end of said shield and non-conductively connected therewith, and electrical means connecting said heater element and said emitter element for supplying a difference of potential between said elements.

DAVID E. KENYON.
